UNITED STATES PATENT OFFICE.

JOSEPH BARRETT, OF NEW YORK, N. Y., ASSIGNOR TO THE PARKS CARPET COMPANY, OF PALMER, MASSACHUSETTS.

DESIGN FOR A CARPET-PATTERN.

Specification forming part of Design No. 5,756, dated April 9, 1872.

To all whom it may concern:

Be it known that I, JOSEPH BARRETT, of the city of New York, have invented or produced a new and original Design to be In-wrought into Brussels and other Carpeting, in suitable colors; and I do hereby declare that the photograph accompanying this specification does give a description of the nature of my invention sufficiently to enable any one skilled in the art of carpet-weaving to use my invention.

What I claim as my invention, and desire to secure by Letters Patent, is—

The configuration of the design hereunto annexed, when applied to carpeting in the form similar to the drawing or photograph accompanying this specification. Pattern No. 532.

JOSEPH BARRETT.
